Des. 868

James L. Howard, of Hartford, Conn.
Letters Patent No. 868. Dated, Jan'y 27th 1857.

The Schedule referred to in these Letters Patent and making
part of the same.

To all whom it may concern.

Be it known that I, James L. Howard, of the City and County of Hartford, in the State of Connecticut, have invented or produced a new and original design for a Rail, Road, or Stove, and I do hereby declare that the following is a full and exact description of the same, reference

being had to the annexed drawings making a part of this specification, in which

Figure 1, is a plan of the top plate, and

Figure 2, a projection of the bottom plate of the outside casing of the stove.

Figure 3, an elevation of the fire door in its frame.

Figure 4, a section of the top plate from z to y, in figure 1, and

Figure 5, a section of the door and its frame from x, to w in figure 3.

The design for the top plate is composed of the circular rope-work band A, around the pipe-hole in the centre of the swelling plate; the diverging rays B, of open, ornamental lattice-work, with the eyelet-like punctures C, in the solid intervening portions; and the ornamented waving border moulding D. The design for the bottom plate consists of the ornaments, a, arranged upon the border moulding E. The design for the door consists of the broad moulding F, and the central tablet G, with ornamental frame h, backed by the closed lattice-work H.

What I claim as my invention or production and desire to secure by letters patent, is

The ornamental design and configuration of the top plate, of the bottom plate, and of the door herein described and represented in the annexed drawings.

Witnesses.

John Moran
A. F. Parks

James L. Howard.
